UNITED STATES PATENT OFFICE.

BENJAMIN H. PURSELL, OF NAPA JUNCTION, CALIFORNIA.

FARM-GATE.

SPECIFICATION forming part of Letters Patent No. 745,663, dated December 1, 1903.

Application filed June 19, 1903. Serial No. 162,296. (No model.)

To all whom it may concern:

Be it known that I, BENJAMIN H. PURSELL, a citizen of the United States, residing at Napa Junction, in the county of Napa and State of California, have invented certain new and useful Improvements in Farm-Gates; and I do hereby declare the following to be a full, clear, and exact description of the same, such as will enable others skilled in the art to which it appertains to make and use the same.

This invention, generally speaking, relates to improvements in gates; but, to be more specific, it is an improvement in that class of gates in which provision is made for the opening and closing of the gate from a point some considerable distance from the same.

It has for its objects to produce a gate of this character which will not sag, but rise as it opens to clear obstacles, and which will possess all the requisites of strength and durability, besides being especially simple in construction and efficient in operation.

I have made provision for insuring against the destructive jar of the gate on the latch and have arranged the parts with a view of resisting to a considerable extent any tendency toward accidental opening.

In following this specification, in conjunction with the accompanying drawings, other advantages of the gate will be seen by those familiar with this class of devices.

I have clearly illustrated the invention in the accompanying drawings, in which—

Figure 1 is a side elevation of the gate in a closed position. Fig. 2 is a perspective view of the gate in a closed position, showing the operative means. Fig. 3 is a perspective view of the top of the post to which the gate is hung. Fig. 4 is an elevation of the gate in an open position, showing the relative position of the operative mechanism. Fig. 5 is a top view of the stop-post employed.

I will now set forth the general construction of the gate and subsequently describe the operation of the same, reference being had to the above views by characters.

The main portion of the gate A is formed of a lower and an upper bar B and C, respectively, forward and rear standards *a* and *b*, respectively, and a series of parallel intermediate bars D.

As a means for supporting the gate I have

provided the stationary post E, on the upper end of which is set the plate *d*, the latter receiving near its front edge a pivotal pin *e*, 55 which passes through the top bar C. This top bar C projects past the post E and is provided at its rear extremity with the hook *f*. Engaging with this hook *f* is the lever F, the lower short arm of which is connected with 60 the lower rear side of the post E by means of the adjustable rod G. The lower rear corner of the gate is slidably connected to the post E by means of the rod H. The spring-latch I engages with a suitable plate on stationary 65 post J.

From the description so far gone into it will be readily seen that as the ropes *g* or *h* are drawn in either direction the tension of the lever F on rod G will elevate the forward 70 end of the gate until the latch leaves its plate, when the gate will continue to rise as it swings open into the position shown in Fig. 4. Drawing the lever F in the opposite direction closes the gate. 75

In Figs. 2 and 4 I have shown mechanism for operating the lever F. It consists of opposite yokes 1 and 2, set in the roadway and connected to pivoted arms 3 and 4, the latter being connected to lever F by means of suitable cables *g* and *h*. The cords 5 and 6, which connect arms 3 and 4 with yokes 1 and 2, are forked and straddle cables *g* and *h*, as shown. Now, assuming that a vehicle is moving in the direction of the arrow in Fig. 4 and has 85 passed over yoke 1, the arm 3 will draw cable *h* until the gate is raised off the latch and opened, as shown in Fig. 4. As the vehicle passes through the open gate and has turned yoke 2 the arm 4 will draw cable *g* 90 until the gate is closed. In order to relieve the latch of the jar of the gate, I have provided the stop-post M, on which is pivoted the dog *m*. As the gate is opened it is raised clear of the dog. 95

The construction and arrangement of the several parts of my gate being thus made known, the operation and the advantages of the same will, it is thought, be readily understood.

I am aware that changes in the form and proportion of parts of the devices herein shown and described as an embodiment of my invention can be made without departing

from the spirit or sacrificing the advantages thereof, and I therefore reserve the right to make such changes, substitutions, and alterations as fairly fall within the scope of my invention.

Having thus fully described the construction of my invention, what I claim, and desire to secure by Letters Patent, is—

1. A device of the class described consisting of a stationary post, a gate formed with an extending top bar, said bar extending beyond and pivoted to said post, a lever pivoted to the outer extremity of said top bar, and a rod connecting said lever with the lower portion of said post, and means for operating said lever, for the purpose set forth.

2. A device of the class described consist-

ing of a stationary post, a gate formed with an extending top bar, said bar extending beyond and pivoted to said post, a pivoted guide connecting the lower extremity of said gate with said post, a lever pivoted to the outer extremity of said top bar, and an adjustable rod connecting said lever with the lower portion of said post, and means for operating said lever and thereby opening and closing said gate for the purpose set forth.

In testimony whereof I affix my signature in presence of two witnesses.

BENJAMIN H. PURSELL.
